CELIUS E. RICHARDS, OF NORTH ATTLEBORO, MASSACHUSETTS.

Letters Patent No. 64,145, dated April 23, 1867.

IMPROVEMENT IN HATS.

The Schedule referred to in these Letters Patent and making part of the same.

TO ALL WHOM IT MAY CONCERN:

Be it known that I, CELIUS E. RICHARDS, of North Attleboro, in the county of Bristol, and State of Massachusetts, have invented a new and improved Hat or Bonnet of Paper; and I do hereby declare that the following is a full, clear, and exact description of the same, reference being had to the accompanying drawings, making part of this specification, in which—

Figure 1 is a side elevation of a miss's hat constructed in accordance with my improvement; and

Figure 2 is a top view of the same.

By the well-known methods of making hats or bonnets from straw, palm leaf, and similar material, the material is first reduced to strips of suitable width and length, and these are braided by hand into bands of five strands, more or less, and these bands are sewn together into the requisite form for the hat or bonnet, or the hat or bonnet is built up from the centre of the crown by plaiting a small number of strands of the material together at first, and afterwards adding to and multiplying the number of strands as the circumference of the fabric is increased, or reducing the number of the strands, as the case may require, according to the shape of the article, the ends of the added strands being suffered to protrude a short distance from the inside of the fabric, and, after the work is completed, being trimmed off evenly with the surface, if desired. In lieu of straw, palm leaf, and other natural material, paper has been cut into slips or strips of the required width, and woven or plaited in the manner mentioned, and afterward bound together by means of a dressing of varnish, and finally protected from injury by wetting or moisture by covering the fabric, after it is converted into the desired shape, with one or more applications of the varnish to make it water-proof, upon which the durability of the fabric, as well as the shape of the article, chiefly depends.

The object of my invention, however, is to employ paper in such a form as to be equally durable with the straw or palm leaf, and be treated in all respects like those materials in the variety of manipulations and the usage to which hats and bonnets are likely to be subjected.

My improvement consists in fabricating hats, bonnets, and similar articles from paper twisted while moist with some glutinous material into thread or twine, and afterwards braided into plaits or bands, or woven or plaited together in the usual way. By twisting the fibres of the paper they are united firmly and compactly together, which gives the material great strength and durability, which is greatly enhanced in the fabric when a multitude of such threads or twines are woven or plaited together, so that the hat or bonnet that is fabricated from paper in this way possesses all the durability of straw or palm leaf, and from the nature of the material it may be treated by the same processes and subjected to the same usage and exposure to the weather without injury.

The kinds of paper which I prefer for the fabrication of my improved hat or bonnet, are those made from straw or grasses, or similar vegetable material, as such paper may be dyed and bleached by the same processes and with the same substances as are now employed by manufacturers and others in palm-leaf and straw goods, so that my improved article may be readily substituted for those of straw, &c., with advantage to both the manufacturer and consumer.

There is a considerable advantage growing out of the fabrication of hats and bonnets of paper, thread, or twine, in the ability to produce such articles at a cheaper cost than can be possible with any material composed of detached lengths or pieces like those of straw and palm leaf heretofore employed, in that the said paper, thread, or twine can be produced in a continuous piece of any length, and be spooled and braided upon well-known machinery for spooling other threads and twines, and with the same rapidity, so that hand-braiding may be entirely dispensed with, thereby reducing the cost of producing all the varieties of this kind of braid more than one hundred fold. My said improvement is obviously applicable to the fabrication of hats, caps, and bonnets of various forms, all of which are included under the term hat, as a covering for the head.

Having described my invention, what I claim, and desire to secure by Letters Patent, is—

A hat fabricated of paper thread or twine, substantially as described, as a new manufacture.

CELIUS E. RICHARDS.
